UNITED STATES PATENT OFFICE.

FRANÇOIS L. GUILMET, OF SAN FRANCISCO, CALIFORNIA, ASSIGNOR
TO THE WESTINGHOUSE AIR BRAKE COMPANY, OF WILMERDING,
PENNSYLVANIA.

AIR-BRAKE.

SPECIFICATION forming part of Letters Patent No. 608,599, dated August 9, 1898.

Application filed June 3, 1896. Serial No. 594,092. (No model.)

To all whom it may concern:

Be it known that I, FRANÇOIS L. GUILMET, a citizen of France, (but having declared my intention to become a citizen of the 5 United States,) residing at San Francisco, in the county of San Francisco and State of California, have invented or discovered a certain new and useful Improvement in Air-Brakes, of which improvement the following is a specification.

The object of my invention is to provide an improvement in automatic fluid-pressure brake apparatus; and to this end my invention consists in a new and improved means 15 for effecting a local exhaust of fluid from the train-pipe of an automatic fluid-pressure brake system, in the combination of such means with a triple-valve device, and in certain combinations and features of construction, all as hereinafter fully set forth.

In the accompanying drawings, which illustrate an application of my improvement, Figure 1 is a central longitudinal section of a quick-action triple-valve device constructed 25 in accordance with my invention; Fig. 2, a transverse section on the line $x-x$ of Fig. 1; Fig. 3, a view of the face of the main valve of the triple-valve device; Fig. 4, a similar view of the face of the graduating-valve of 30 the triple-valve device; Fig. 5, a transverse section of the valvular stem which projects from the piston of the triple-valve device, the section being taken on the line $z-z$; and Fig. 6, a transverse section through the same stem 35 on the line $y-y$.

The main casing 1 of the triple-valve device contains the piston-chamber 2 and the main-valve chamber 3, and a cap-section 4, which forms a cover for the piston-chamber, 40 is secured thereto by means of bolts 5. The cap-section 4 is connected with the train-pipe or with a branch therefrom by means of a screw-threaded nozzle 6, which is provided with a passage 7, communicating with the interior of the train-pipe and connected with the piston-chamber 2 by means of a passage 8.

An emergency-valve 9, which controls the local release of fluid from the train-pipe, cuts off communication normally and during service 45 ice applications between the passage 7 and

the passages 10 and 11, leading to the brake-cylinder. An annular face on the valve 9 is provided with a gasket 12, which bears on a seat 13, and the end of a tubular extension 14 bears on a gasket 15, fitted in the casing on one side of the passage 10. A central hub 16 55 is connected to the tubular extension 14 by means of webs 17, and a stem 18 is fitted to slide in the hub, the extent of the sliding movement in one direction being limited by a shoulder 19, formed on the stem, and in the other direction by a nut 20, secured to the end of the stem. The stem 18 extends through the dividing wall or partition 21 into a chamber 22, which is in open communication with the piston-chamber 2, and a spring 23, surrounding the stem 18, bears at one end against a collar 24, formed on the stem, and at the other end against a gasket 25, which is fitted around the stem and forms a packing for the joint around the stem to prevent the passage of fluid through the opening in the partition 21.

The triple-valve piston 26 normally uncovers a feed-passage 27 in the bushing 28, 75 through which fluid under pressure from the train-pipe is admitted to a passage 29, leading to the auxiliary reservoir. Secured to the stem 30 of the triple-valve piston is a graduating slide-valve 31, whose stem 42 80 passes through the stem of the piston and is acted on by a spring 33, which is secured to the main valve 34 and tends to keep both valves to their seats on the bushing 32.

The main valve 34 is located between the 85 graduating-valve 31 and the shoulder 35 on the stem 30 and is of such length as to permit the necessary independent movement of the stem 30 and graduating-valve 31.

The main-valve chamber 3 communicates 90 with the auxiliary reservoir through the passages 36 and 37, and the passage 11, which leads to the brake-cylinder, is normally in communication with the atmosphere through the passages 38 and 39, which are connected 95 by the cavity 40 in the main valve when the main valve is in release position.

A stem 41 projects from the piston 26 into the passage 8, in which is fitted a bushing 43, through which the stem 41 moves as the pis- 100

ton 26 is moved back and forth. A portion of the stem 41 is provided with grooves 44, which permit a free passage of fluid between the piston-chamber 2 and the passage 8 when 5 the piston 26 is in position to release the brakes or in position to make a service application of the brakes; but the length of these grooves is such that they are moved entirely into the passage 8 when the piston 26 is moved to the 10 limit of its stroke to the left. A groove 45, which extends the whole length of the stem 41, forms a limited passage for fluid from the train-pipe through the passage 8 to the left-hand side of the piston 26 when the piston is 15 at the limit of its stroke to the left.

In making service applications of the brakes a comparatively slight reduction of train-pipe pressure will permit the auxiliary-reservoir pressure on the right of the piston 26 to move 20 the piston to the left until the stem 40 comes in contact with the stem 18 and the spring 23 is slightly compressed, when the resistance of the spring 23 will prevent further movement of the piston. By this movement of the piston 25 ton the graduating-valve 31 is moved into contact with the main valve 34, the main valve is moved to the left, so as to cut off communication between the passages 38 and 39, and both the main and graduating valves 30 are moved to the left of the passage 47, through which fluid under pressure flows from the auxiliary reservoir to the passage 11 and to the brake-cylinder.

When the auxiliary-reservoir pressure has 35 been reduced by expansion into the brake-cylinder until it is about equal to the pressure in the train-pipe, the piston 26 will be moved to the right until the shoulder 35 on the stem 30 abuts against the main valve, 40 when the resistance of the main valve will prevent further movement. The graduating-valve 31 will then be in position to close the passage 47, and the flow of fluid from the auxiliary reservoir to the brake-cylinder will be 45 cut off. A further slight reduction of train-pipe pressure will cause the piston to be again moved to the left, the graduating-valve 31 will again open the passage 47, and fluid from the auxiliary reservoir will again flow 50 to the brake-cylinder. This may be repeated as often as desired or until the auxiliary-reservoir and brake-cylinder pressures have equalized.

In service applications of the brakes the 55 movement of the stem 18 is not great enough to bring the shoulder 19 into contact with the central hub on the emergency-valve 9, and the valve 9 remains on its seat, to which it is held by train-pipe pressure.

60 When a great and rapid reduction of train-pipe pressure is made, such as is necessary to effect an emergency application of the brakes, the piston 26 is moved to the left until the inner ends of the grooves 44 in the 65 stem 41 are within the passage 8, and communication between the passage 8 and the piston-chamber 2 is closed except through the

comparatively small passage 45 in the stem 41. The main valve has then been moved far enough to the left to bring the cavity 50 70 into position to connect the port 51 in its seat with the passage 38, and fluid under pressure will be exhausted from the piston-chamber 2 and chamber 22 through the passage 52, port 51, cavity 50 in the main valve, and passages 75 38 and 11 to the brake-cylinder. Since the capacity of these passages is greater than the capacity of the groove 45 in the stem 41, the pressure in piston-chamber 2 will be quickly and greatly reduced, and the rapid 80 movement of the piston 26 to the limit of its stroke to the left will be insured. As the piston 26 moves to the left the stem 46 comes in contact with the stem 18 of the local exhaust-valve 9, the spring 23 is compressed, 85 and the shoulder 19 on the stem 18 comes in contact with the hub 16 of the valve 9 and unseats that valve. Fluid under pressure from the train-pipe then flows through the passage 7 and through the valve 9 into the 90 passage 10 and, unseating the check-valve 53, flows through passage 11 to the brake-cylinder. At the same time fluid under pressure from the auxiliary reservoir flows through the passages 47 and 11 to the brake-cylinder 95 and continues to flow until the auxiliary-reservoir and brake-cylinder pressures are equalized.

If an ordinary check-valve is employed between the passages 10 and 11, the check-valve will close when the pressure in the brake-cylinder is nearly equal to that in the train-pipe and prevent any return flow of fluid from the brake-cylinder to the train-pipe; but with the construction shown in the 105 drawings a gradual return flow of fluid from the brake-cylinder to the train-pipe is permitted. The check-valve 53 is provided with an extension 54, which is closely fitted in the bushing 55, and a small groove 56 in the extension 54 permits the passage of fluid except when the conical face of the valve 53 is on its seat. A small spring 57 surrounds the stem 58 of the check-valve and tends to hold it on its seat; but the action of this spring is resisted by a spring 59, which bears at one end 110 on a nut 60 and at its other end on a loose collar or washer 61, which, as shown in the drawings, rests on a fixed bearing. The spring 59 tends to hold the valve 53 from its seat 115 when the collar is in contact with the fixed bearing, and fluid from the brake-cylinder is then permitted to flow gradually through the groove 56 and return to the train-pipe. The resistance of the spring 59 is such that the 120 valve 53 will not be closed completely by the usual excess of equalized auxiliary-reservoir and brake-cylinder pressure over that in the train-pipe; but in case of a rupture in the train-pipe or the parting of the pipe-couplings 125 the excess of pressure in the brake-cylinder 130 and passage 11 will be sufficient to overcome the resistance of the spring 59, and the valve will be completely closed. After such a great

reduction of pressure in the train-pipe as soon as the train-pipe is again partially recharged the spring 59 will unseat the check-valve 53 and the pressure in the auxiliary reservoir and brake-cylinder will be permitted

5 to return to the train-pipe until the fluid-pressure, acting on the piston 26, moves it to the right and the pressure of the spring 23 shifts the stem 18 and closes the valve 9.

10 It will be seen that while the spring 59 resists the complete closing of the valve 53 it has no effect on the opening or closing movement of the valve after the valve has been moved a certain distance from its seat. The 15 collar 61 then bears on the shoulder 62 on the valve-stem, and so long as the collar is out of contact with the fixed bearing 63 it has no effect on the valve.

When the triple-valve piston 26 has moved 20 to the limit of its stroke to the left, the flanges or annular ridges 48 and 49 bear on the gasket 64, and the flange or annular ridge 49 forms a tight joint with the gasket and cuts off communication between the train-pipe and 25 the chamber 22, thereby preventing the return of fluid from the brake-cylinder to the train-pipe through the passages 11 38 52, chambers 22 and 2, and passage 8.

I claim as my invention and desire to secure 30 by Letters Patent—

1. The combination, in a triple-valve device, of a piston exposed on its opposite sides to fluid under pressure, a valve operated by the piston for releasing fluid under pressure 35 from the auxiliary reservoir to the brake-cylinder and controlling a passage, or passages, through which fluid under pressure is released from one side of the piston to effect an emergency application of the brakes, substantially 40 as set forth.

2. The combination, in a triple-valve device, of a piston, a valve operated by the piston for releasing fluid under pressure from the auxiliary reservoir to the brake-cylinder and 45 controlling a passage, or passages, through which fluid under pressure is released from the train-pipe side of the piston to effect an emergency application of the brakes, substantially as set forth.

50 3. The combination in a triple-valve device, of a piston, a main valve operated thereby for releasing fluid under pressure from the auxiliary reservoir to the brake-cylinder, a local exhaust-valve operated by movement of 55 the piston, and a passage, or passages, con-

trolled by the main valve, and through which fluid under pressure is released from one side of the piston to effect opening movement of the local exhaust-valve, substantially as set forth.

60 4. The combination, in a triple-valve device, of a piston exposed on one side to train-pipe pressure, a valve operated by the piston for applying the brakes in service applications, means for limiting the capacity of the 65 passage by which the piston-chamber communicates with the train-pipe, a passage, or passages, controlled by the valve for releasing fluid under pressure from the train-pipe side of the piston, and a local exhaust-valve 70 operated by the piston to release fluid under pressure from the train-pipe, substantially as set forth.

5. The combination, in a triple-valve device, of a piston, a valve operated thereby for 75 releasing fluid under pressure from the auxiliary reservoir to the brake-cylinder by a partial movement of the piston, and to release fluid under pressure from the train-pipe side 80 of the piston by a further movement of the piston, and a local exhaust-valve operated by a final movement of the piston, substantially as set forth.

6. The combination, in an automatic fluid-pressure brake apparatus, of a local exhaust- 85 valve controlling the release of fluid under pressure from the train-pipe to the brake-cylinder, a check-valve in the passage between the train-pipe and the brake-cylinder, and a spring adapted to hold the check-valve 90 partially open, to permit a return flow of fluid from the brake-cylinder to the train-pipe, and to permit the closing of the valve on an excessive reduction of pressure in the train-pipe, substantially as set forth.

95 7. The combination, in an automatic fluid-pressure brake apparatus, of a local exhaust-valve for releasing fluid under pressure from the train-pipe to the brake-cylinder, a check-valve in the passage between the train-pipe 100 and the brake-cylinder, a spring tending to close the check-valve and a spring tending to hold the check-valve partially open, substantially as set forth.

In testimony whereof I have hereunto set 105 my hand.

FRANÇOIS L. GUILLEMET.
